US00D706176S

(12) United States Design Patent
Oberg

(10) Patent No.: US D706,176 S
(45) Date of Patent: * Jun. 3, 2014

(54) ROTATING CYCLE REFLECTOR

(71) Applicant: Anne Oberg, Longmont, CO (US)

(72) Inventor: Anne Oberg, Longmont, CO (US)

() Term: 14 Years

(21) Appl. No.: 29/448,808

(22) Filed: Mar. 13, 2013

(51) LOC (10) Cl. 12-11

(52) U.S. Cl.

USPC D12/114

(58) Field of Classification Search
